UNITED STATES PATENT OFFICE.

HIRAM PERCY MAXIM, OF HARTFORD, CONNECTICUT.

BUILDING-SILENCER.

1,289,856.

Specification of Letters Patent. Patented Dec. 31, 1918.

Application filed December 18, 1917. Serial No. 207,781.

To all whom it may concern:

Be it known that I, HIRAM PERCY MAXIM, a citizen of the United States, residing at Hartford, in the county of Hartford and 5 State of Connecticut, have invented certain new and useful Improvements in Building-Silencers, of which the following is a specification.

This invention relates to what I might 10 for convenience term a "building silencer." As will be inferred the silencing means can with advantage be used in conjunction with structures of widely different classes. It is of particular utility, however, when associated with or forming part of a human habitation whether the same comprises one or more compartments or rooms. An illustration of a building of this character is a hotel or apartment house. While as I observe, 15 the invention is of prime importance in this particular field, I am in no sense restricted thereto, for it is conceivable that it might be used in other connections, for example a hospital where noise is especially 20 objectionable. One of the fundamental purposes I have in view is the provision of means for the elimination as far as practicable certainly, of noise from a room or compartment without affecting the proper 25 entrance of air, and when required the supply of a cooling or a heating agent thereto. I therefore provide in connection with a room intended for human habitation, means for ventilating the room, and positive 30 silencing means applied to damp or check all noise vibrations of the air entering said room. While as I have noted, the invention is susceptible of general use, I have for the purpose of showing its nature, illustrated 35 it in one of its several forms as presenting a part of what might be considered either an apartment house or hotel. This showing is provided to enable those skilled in the building and allied arts to comprehend 40 the improvement. As will be clear I am not restricted to this disclosure; I may depart therefrom in several respects within the scope of the invention defined by the 45 claims following said description.

50 Referring to said drawings:

Figure 1 is an elevation partly in section of a building equipped with silencing means involving the invention.

Fig. 2 is a horizontal section on the line 55 2-2 of Fig. 1, looking in the direction of the arrow.

Fig. 3 is a horizontal section of a group of rooms.

Fig. 4 is a detail in section of a duct.

Fig. 5 is a horizontal section on the line 60 5-5 of Fig. 1, looking in the direction of the arrows.

Figs. 6 and 7 are vertical sections on the lines 6-6 and 7-7 respectively of Fig. 3, looking in the directions of the arrows applied to the respective lines.

Like characters refer to like parts throughout the several views which as will be clear, are on widely different scales.

I have already made it clear that the invention is capable of general use. In Fig. 1 I have shown practically in full a building 70 as 2. This building may be either a hotel or apartment house. The number of stories is not a matter of moment. Each living 75 room I have denoted by 3. Obviously these rooms may be of any number on each floor. The halls on each floor are denoted by 4. The size of the rooms, their arrangement and similar remarks applying to the 80 halls, are it will be understood not matters of importance. In reality there may be a structure where there is no hall or even an equivalent. The living rooms 3 as I might consider them, are provided with windows 85 5, while the halls 4 have practically similar windows 6. In like manner this in itself is not a feature of importance. It is in effect vital, however, that in all seasons I can keep these windows shut without interfering with the proper supply of the necessary constituents to maintain life and at the same time furnishing either heat or cold in conformity naturally with the season or the individual taste. By closing the windows 90 5 I not only exclude exterior sounds which is a point of value, but what is of greater importance exclude the entrance of dust and other foreign matter into the room or rooms. This I accomplish, of course, without affecting 95 the vision of an occupant as to what is occurring outside the building.

Extending depthwise of the building 2 for example at the center, although this may not always be necessary, is a shaft or well 7 open 100 at its top for the entrance of a duct member as 8 which might be considered as a main. This duct member or main 8 is virtually coextensive with the depth or height of the building as common in several different arts. It extends above the roof of the building and is associated in an operative 110

manner with a suitable silencing appliance such as that denoted in a general way by 9. This silencing appliance comprises as shown an outer and practically cylindrical shell 5 or body 10. This body or shell 10 is closed top and bottom as at 12 and 13 respectively, the top being practically flat, while the bottom 13 tapers downward, and the duct member or main 8 is connected centrally with the 10 bottom 13. As a result of this the duct member communicates with the interior of the casing or shell 10. The casing or shell 10 incloses a cylindrical wall 14 extending from the top 12 to the bottom 13 unbrokenly. 15 Below the bottom 13 is the flange 15 which presents in effect a continuation of the wall or partition 14. This wall or partition 14 is of course, spaced or separated from the wall of the casing or shell 10, and the reason for 20 this will hereinafter be set forth. The top 12 has as shown a central opening 16 for the admission of atmospheric air, silencing means as will be clear being interposed in the path of the atmospheric air, in view of 25 which circumstance the air will be supplied to the various rooms as I will hereinafter point out as free from sound as possible. Connected with the top 12 and depending therefrom for a certain distance is the vane 30 17, this vane being practically of spiral form. Its upper edge is united to the top 12 around the opening 16. Around this vane 17 is a larger vane 18, while in turn around the vane 18 is a third vane 19. All 35 three of these vanes as will be understood are connected with the top 12. They are united at the bottom by the plate 20 which is spaced from the bottom 13. The vanes 17, 18 and 19 have outlets 21, 22 and 23 40 which are in staggered relation with each other, that is to say the outlet 21 is not in radial line with the outlet 22, nor is the latter in radial line with the outlet 23, as will be seen best on inspection of Fig. 2. It 45 will be clear, therefore, that atmospheric air enters the silencer 9 by way of the inlet 16, passing from thence into the spiral tube 17, leaving the outlet 21 of the latter and entering the space surrounded by the vane 18, 50 passing through the outlet 22 and entering the space surrounded by the outer vane 19, being discharged through the outlet 23 into the chamber inclosed by the cylindrical wall 14, to which I have already referred and taking 55 a downward course and entering the duct or main 8 from which it is conveyed, as I will hereinafter explain to the several rooms 3 and halls 4.

The parts of the silencer 9 to which I have 60 already referred are generally made from metal, although this is not a primary consideration. The substance in question, however, is satisfactory. To augment the effect of the silencer its various interior surfaces 65 may be provided with a sound-deadening

substance as 24 which may consist of felt or other convenient material adhesively united to the surface. As I will hereinafter point out this same material is connected to other surfaces in the path of the air. In the main 70 8 I may position a heat modifying element as 25 which as shown consists of a coil located in the vicinity of the silencer 9. To this coil may be supplied a suitable medium for instance steam in cold weather or a refrigerant 75 in warm weather. I may also force the air into the main 8, and for this purpose may provide a suitably driven fan 26 located practically at the entrance of the main 8. This fan obviously draws atmospheric air 80 into the inlet 16 and drives it into the main 8 to be subsequently supplied to the various rooms and halls of the building.

As I have already explained one of the purposes of the main 8 is to furnish fresh air 85 to the several rooms 3 and halls 4, and this can be obtained in any desirable manner. As shown the main 8 has leading therefrom in suitable order and laterally, the branches 27 joined to openings 28 in the walls of the 90 respective rooms and halls. These openings 28 are near the ceilings of the several rooms and halls. The rooms and halls in turn have openings 29 therein situated near the floors thereof. From the respective branches 27 95 extend branch flues as 30 leading to the respective openings 29. The branches 27 are located in or near the ceilings, while the branches 30 may be in the walls. The openings 28 and 29 are provided respectively with 100 valves which I shall for convenience denote as 31 in each case. In summer it is desirable that the cold, fresh and silenced air enter the rooms and halls in the upper portions thereof, say near the ceilings. In this 105 case the upper dampers or valves 31 as shown in Fig. 7 will be opened to accomplish this particular result. In winter or cold weather when warmth is desirable if not imperative, this condition will be reversed, the upper valves or dampers 31 being closed and the lower ones being opened, in view of which latter result it follows that the 110 silenced and warm air enters the rooms and halls at or near the floors thereof.

I provide means for carrying off the stagnant or foul air, and this without the necessity of opening the windows or doing some other thing which would result in the entrance of objectionable or undesirable noises 115 or sounds. It is practically necessary that the air generally stagnant or in effect in that condition, should be conveyed from the rooms and halls. For this purpose I provide for instance in the partition walls, 120 flues 32, the walls of the several rooms and halls having openings 33 connecting said rooms and halls with these flues. As shown the openings 33 are situated at or near the floors as the foul air descends. Passing 125 130

from the rooms or halls by way of the openings 33 into the flues 32 it ascends, leaving the upper ends of the flues and passing into the connecting flue 34 on the roof of the building 2. From this connecting flue 34 is the discharge duct 35 opening into the silencer 9 and having direct communication with the space between the shell or body 10 and the partition 14. From the casing 10 leads the discharge connection 36 from which the foul air is finally discharged into the atmosphere. The several discharge flues and their connections just described may be lined with silencing material as indicated at 15 37. The air thus discharged acts before it reaches the atmosphere to either initially heat or cool the incoming air.

What I claim is:

1. The combination of a room intended 20 for human habitation, means for supplying air to the room, and positive silencing means applied to said air supplying means.

2. The combination of a room intended 25 for human habitation, a flue leading from the outside atmosphere to said room, and positive silencing means in correlation with the room and the flue for silencing the air entering the room by way of said flue.

3. The combination of a room intended 30 for human habitation, means for the supply of air to the room, positive silencing means applied to damp or check noise vibrations in said air, and means for modifying the air supplied to the room.

35 4. The combination of a room intended for human habitation, a main having branches leading to the upper and lower sides of the room for the supply of air thereto, means for shutting off the air as desired to the upper and lower portions of the room, and silencing means applied to damp or check noise vibrations in said air.

40 5. The combination of a room intended for human habitation, a main having 45 branches leading to the upper and lower

sides of the room for the passage of air, means for shutting off the supply of air as desired to the upper and lower portions of the room, definite silencing means applied to damp or check noise vibrations in said air, 50 and air modifying means associated with the main.

6. The combination of a room intended for human habitation, a noise silencer having an air inlet, and a main leading from the 55 silencer to the room.

7. The combination of a room intended for human habitation, a noise silencer having an air inlet, a main leading from the silencer to the room, and a heat modifying 60 appliance in the main between the silencer and the room.

8. A room, a silencer having an air inlet, means for conducting air from the silencer to the room, and means for conducting air 65 from the room to the silencer.

9. The combination of a room intended for human habitation, means for supplying air to the room, definite silencing means applied to damp or check the noise vibrations 70 in the air, and means for discharging air from the room and causing the outgoing air to modify the incoming air.

10. The combination of a room intended for human habitation, and positive silencing 75 means arranged to damp or check any sound producing air vibrations from entering said room.

11. In combination a room intended for human habitation, means for ventilating said 80 room, and positive silencing means applied to damp or check noise vibrations of the air entering said room.

In testimony whereof I affix my signature in the presence of two witnesses.

HIRAM PERCY MAXIM.
